UNITED STATES PATENT OFFICE.

PETER STOLTZ, OF BERLIN, GERMANY.

THE FEEDING OF FUEL TO INTERNAL-COMBUSTION ENGINES.

1,194,567.

Specification of Letters Patent. Patented Aug. 15, 1916.

Application filed June 26, 1912. Serial No. 705,900.

To all whom it may concern:

Be it known that I, PETER STOLTZ, a subject of the German Emperor, residing at Hafenplatz 8, Berlin, Germany, engineer, have invented certain new and useful Improvements in and Relating to the Feeding of Fuel to Internal-Combustion Engines, of which the following is a specification.

The present invention has for its object an internal combustion engine operating with liquid fuel in which in the known manner the fuel is sprayed into the combustion air which has been compressed at least in part.

The invention has for its object to adapt engines of this kind for high speeds of rotation such as are necessary for driving vehicles.

The internal combustion engines in which the fuel is sprayed in as hitherto known can only attain high speeds with difficulty mainly because unless special measures are taken the flow of fuel is interrupted in the suction pipe of the fuel pump owing to the great acceleration at the beginning of each suction stroke so that the fuel pump ceases to furnish its supply. In other words, the pump when exceeding a critical speed is unable to suck into the pump chamber the required charge of liquid fuel during the extremely short time interval between successive fuel delivering strokes of the pump piston. On the other hand owing to the high piston speed of the fuel pump the injection produced by its pressure stroke is not sufficiently controllable so that in practice it is necessary to have recourse to the atomizing of the fuel by compressed air which is not a desirable auxiliary means. In accordance with the invention these difficulties are overcome owing to the fact that a number of fuel pumps are provided for one motor cylinder; these pumps are connected in parallel and deliver in succession to supply the fuel so that, for example, if three fuel pumps are used each of these pumps injects fuel into the engine cylinder once only during three power strokes of the engine piston and each pump piston makes only one-third the strokes that would be necessary if but one pump were provided. This permits each pump to have approximately three times the amount of time to suck in its charge and thus proper charges are insured and regulation of the charge rendered less difficult.

It is advantageous to provide for each

pump at least one special injection valve on the combustion cylinder so that the injection valves operate in succession and the difficulties hitherto arising owing to the high speed of operation of the injection valve are avoided.

The drawing is a diagrammatic plan of two different arrangements of the fuel pumps.

In Figure 1 each of the two fuel pumps *e* 65 co-operates with a separate injection member (atomizing valve) *b* on the cylinder *a* while in Fig. 2 both the pumps deliver to one and the same injection member. In both cases each fuel pump need only effect one operative stroke for every two cycles in the motor cylinder.

As already stated in some cases the arrangement shown in Fig. 1 is considerably more advantageous because here each valve *b* 75 runs at only half the speed of the valve *b* in Fig. 2.

The motor can be regulated for example by means of a throttling member *h* arranged in front of the fuel pumps and arranged in 80 the common fuel supply pipe *g* or by means of a plurality of throttling members which are distributed on the branch pipes leading to the several fuel pumps. This regulation acts in such a manner that according to the 85 throttling of the member *h* only a portion of the stroke volume of the pump is filled with fuel. Upon the retractive stroke of the pump piston the vacuum is first compensated for and then toward the end of the stroke, 90 the quantity of fuel drawn in which is determined by the throttling is delivered into the combustion chamber.

What I claim and desire to secure by Letters Patent of the United States is:

1. A high speed internal combustion engine of the Diesel type having a combustion chamber, a plurality of liquid fuel pumps operated by said engine and delivering to said chamber in succession, each of said pumps serving to supply the liquid fuel for a separate power stroke of the engine piston, and independently controllable valves for separately regulating the admission of liquid fuel to each of said pumps. 100

2. A high speed internal combustion engine, of the Diesel type, having a combustion chamber provided with a plurality of separate liquid fuel inlets, a plurality of liquid fuel pumps operated by said engine and de- 110

livering from the same source of supply to
said chamber and in succession, each of said
pumps delivering through a separate inlet
and serving to supply the liquid fuel for a
5 separate power stroke of the engine piston,
and controllable valves for regulating the ad-
mission of liquid fuel to each of said pumps.

In testimony whereof I affix my signature
in presence of two witnesses.

PETER STOLTZ.
